SEARCHED SERIALIZED FILED

No. 11,872

July 20, 1880

Cut 217, with Planished Reservoir.

UNITED STATES PATENT OFFICE.

OTIS G. CLARK, OF TROY, AND DANIEL D. BUCKLIN, OF LANSINGBURG, EXECUTORS OF NICHOLAS S. VEDDER, DECEASED, AND TOBIAS S. HEISTER, OF LANSINGBURG, NEW YORK; SAID HEISTER ASSIGNOR TO SAID CLARK AND BUCKLIN AS EXECUTORS.

DESIGN FOR A COOKING-STOVE.

SPECIFICATION forming part of Design No. 11,872, dated July 20, 1880.

Application filed June 14, 1880. Term of patent 3½ years.

To all whom it may concern:

Be it known that NICHOLAS S. VEDDER, deceased, late of the city of Troy, in the county of Rensselaer and State of New York, and 5 TOBIAS S. HEISTER, now residing in the village of Lansingburg, in said county and State, did jointly invent and produce a certain new and original Design for Cooking-Stoves; and that OTIS G. CLARK, residing in the city of 10 Troy, aforesaid, and DANIEL D. BUCKLIN, residing in the aforesaid village of Lansingburg, are the executors of the last will and testament of said NICHOLAS S. VEDDER, deceased; and we, the said OTIS G. CLARK, 15 DANIEL D. BUCKLIN, and TOBIAS S. HEISTER, hereby declare that the following is a specification of the said new design, reference being had to the accompanying cut, print, or engraving representing the same.

20 One feature of this invention is the design for the panel ornament A, composed of a central depressed angular panel, b, with a representation of a harp, c, therein, the surrounding frame d, having the obtusely-angled top 25 part, e, with the central angular ornament, f, lateral scroll-leaves g, and corner ornaments, h, thereon, the circular ornaments i; and pendants j at the sides, and the depressed lower portion, k, with the central angular ornament, 30 l, and the corner ornaments, m n, all shaped and arranged together substantially as shown in the aforesaid cut.

Another part of this invention is the design for the oven-door, composed of the compound 35 ornament A and the ornamental border O, consisting of the convex outer molding, p, corner ornaments, q, vine-like ornamentation r, and inner ornamented edging, s, all shaped and arranged as represented in the aforesaid print.

40 Another part is the design for the closet-door, consisting of the compound panel ornament S and the ornamental border O', composed of the outer convex molding, p', corner ornaments, q', and vine-like ornamentation r', all shaped and disposed as represented in the 45 accompanying engraving.

Another part is the design for the fuel door or panel of the fire-box, composed of the compound ornament T and ornamental border O'',

consisting of the convex molding p'', corner 50 ornaments, q'', and vine-like ornamentation r'', all shaped and arranged as represented in the aforesaid print.

Another part is the design for the front door, consisting of the lower projecting oblong rectangular section, U, having the vertically-oblong apertures v, and intermediate and lateral ornaments w, and the upper section, X, having the vertically-oblong lateral apertures y, horizontally-oblong middle aperture, y', and the 60 vine-ornamented border z, all shaped and arranged together substantially as represented in the aforesaid cut.

What is claimed as the joint invention of the aforesaid NICHOLAS S. VEDDER, deceased, 65 and TOBIAS S. HEISTER, aforesaid, is—

1. The design for the panel ornament A, composed of the parts b, c, d, e, f, g, h, i, j, k, l, m, and n, as shown and described.

2. The design for the oven-door, consisting 70 of the compound ornament A and the border O, composed of the parts p, q, r, and s, as shown and described.

3. The design for the closet-door, consisting of the compound panel ornament S and the ornamental border composed of the parts p', q', 75 and r', all shaped and arranged as shown and described.

4. The design for the end door or panel of the fire-box, consisting of the compound ornament T and the ornamental border O'', composed of the parts p'', q'', and r'', all shaped and arranged as shown and described.

5. The design for the front door, consisting of the lower section, U, having the parts v and 85 w, and the upper section, X, having the parts y, y', and z, all shaped, arranged, and combined as shown and described.

In testimony whereof we hereunto set our hands, in the presence of two subscribing witnesses, this 10th day of June, 1880.

OTIS G. CLARK,
DANIEL D. BUCKLIN,
Executors of Nicholas S. Vedder, deceased.
TOBIAS S. HEISTER.
